UNITED STATES PATENT OFFICE.

CHARLES EDWARD MURNAN, OF BROOKLINE, MASSACHUSETTS, ASSIGNOR TO MELLO-GLO COMPANY, OF BOSTON, MASSACHUSETTS, A CORPORATION OF MASSACHUSETTS.

VANITY CASE.

Application filed August 22, 1924. Serial No. 783,539.

To all whom it may concern:

Be it known that I, CHARLES E. MURNAN, a citizen of the United States, residing at Brookline, in the county of Norfolk and 5 State of Massachusetts, have invented new and useful Improvements in Vanity Cases, of which the following is a specification.

This invention relates to a vanity case adapted to hold loose toilet powder and a 10 powder-applying puff.

The chief object of the invention is to provide an improved construction of the portion of the case in which the powder and puff are stored, whereby the puff is 15 caused to securely confine the powder when the case is closed, and is adapted to conveniently take up powder.

Other objects are to provide an improved construction of the mirror-holding cover, 20 and an improved catch adapted to confine the cover in its closed position.

Of the accompanying drawings forming a part of this specification,—

Figure 1 is a plan view of a vanity case 25 embodying the invention.

Figure 2 is a side view of the cover looking toward the inner side thereof.

Figure 3 is a perspective sectional view 30 of the powder receptacle without the cover, the section being on line 3—3 of Figure 1.

Figure 4 is a section on line 4—4 of Figure 1.

Figure 5 is a section on line 5—5 of Figure 1.

Figure 6 is a section on line 6—6 of Figure 4.

Figure 7 is a section on line 7—7 of Figure 4.

Figure 8 is a sectional view showing by 40 dotted lines the open position of the cover.

Figure 9 is a view similar to Figure 8, showing a modified form.

The same reference characters indicate the same parts in all of the figures.

The powder receptacle of my improved case includes a bottom member 12, having an annular outwardly projecting flange 13, and a top member having an annular inwardly projecting flange 14 in close frictional contact with the flange 13 and contacting with the bottom member 12 to maintain the two members spaced apart. The top member is composed of an annular marginal portion 15, a central portion 16, offset

inwardly from the marginal portion, and 55 an annular neck 17, connecting the portions 15 and 16. Said neck forms the margin of a puff receptacle, adapted to receive a powder puff 18, the bottom of said receptacle being formed by the offset portion 16. Said 60 offset portion is provided with a central orifice 19, the diameter of which is preferably about one-third of the diameter of the top member. Said orifice permits the central portion of the puff to be pressed into the 65 powder receptacle and take up powder therein. The flexibility of the top member is so increased by the orifice 19 and the neck 17, that pressure of a finger on the central portion of the puff depresses the central portion of the top member so that the puff is 70 enabled to take up more of the powder than would be the case if the relatively large orifice 19 were not provided.

The puff is held closely pressed against 75 the margin of the orifice 19 by the cover hereinafter described, so that when the case is closed there is no liability of leakage of powder.

21 designates a cover having an annular 80 inwardly projecting flange 22, formed to abut against the bottom member flange 13, as best shown by Figures 4 and 5, and is connected therewith by a hinge 23. The cover, when closed, is adapted to press the 85 puff 18 closely against the top member of the powder receptacle. I prefer to make the cover flange 22 of sufficient width to enable the cover to receive a cushion 24 of any suitable yielding material, such as felt or paper, 90 a mirror 25, seated on the cushion, and a mirror-confining ring 26, seated on the marginal portion of the outer surface of the mirror and engaged by friction or otherwise, with the cover flange to confine the mirror 95 securely against the cushion. The ring 26 bears on the marginal portion of the puff 18, as shown by Figures 4 and 5.

The cover is confined in its closed position by a catch including a spring shank 100 27, interposed and closely confined between the flanges 13 and 14, as shown by Figures 4 and 6, and projecting above the top member of the powder receptacle, and a detent 28, fixed to the free end of said shank and 105 adapted to spring into an orifice in the cover flange 22, as shown by Figure 4. The marginal portion 15 of the top member is pro-

vided with a recess 29 (Figures 4 and 7), permitting the free end of the shank 27 to be sprung inward and release the cover.

The described construction enables the case to be made relatively thin, and at the same time hold a considerable quantity of powder. The thickness of the margin of the case may be reduced as shown by Figure 9.

It is obvious that the flexibility of the top member permits the user to depress the same by exerting pressure on any portion of the puff, the central portion of the top member yielding to pressure exerted on any part of the outer side of the puff.

15 The offset portion 16 is preferably raised around the orifice 19, as shown by Figure 3, so that the margin of the orifice projects outward from the surrounding portion of the portion 16. This formation provides a greater amplitude of springing movement, and a tighter contact between the puff and the margin of the orifice, so that leakage or "spitting" of powder is prevented.

25 The flexibility of the top member enables the puff to take up powder when the receptacle is nearly empty, the puff being permitted to be pressed inward until it practically touches the bottom member 12.

30 It is also obvious that the user may manipulate the puff to take up powder through the orifice 19, without pressing the puff against the top member.

35 The powder in the deeper marginal portion of the powder receptacle may be forced to the central portion under the orifice 19 by suitably manipulating or shaking the case.

I claim:

40 1. A vanity case comprising a powder receptacle including a bottom member having an annular outwardly projecting flange, and a top member having an annular inwardly

projecting flange in close frictional contact with the bottom member flange and contacting with the bottom member to maintain the two members spaced apart, the central portion of the top member being offset inwardly from the marginal portion, provided with a central aperture, and connected with the marginal portion by an annular neck forming the margin of a puff receptacle, the bottom of which is formed by said offset portion, a puff inserted in said receptacle, the arrangement being such that the puff covers said aperture and is adapted to be depressed therein, to take up powder in the powder receptacle; and a cover having a marginal flange hinged to the flange of the bottom member, and adapted to confine the puff in contact with the top member of the powder receptacle, the said aperture imparting flexibility to the offset portion of the top member.

2. A vanity case as specified by claim 1, comprising also a cover-confining catch including a spring shank interposed between the flanges of the bottom and top members and projecting above the top member, and a detent fixed to the free end of said shank and adapted to spring into an orifice in the cover flange, the marginal portion of the top member being provided with a recess permitting the free end of the shank and the detent to be sprung inward.

3. A vanity case as specified by claim 1, comprising also a cushion contacting with the inner surface of the cover, a mirror seated on said cushion, and a mirror-confining ring seated on the marginal portion of the mirror and engaged with the cover flange, said ring being formed to bear on the marginal portion of the pad.

In testimony whereof I have affixed my signature.

CHARLES EDWARD MURNAN.
